CLAIM

The ornamental design for a two piece 20 pound propane tank cover with access lid, as shown and described.

DESCRIPTION

FIG. 1 is a top, right, front exploded perspective view of a two piece 20 pound propane tank cover with access Lid according to the invention. The access lid being removed for clarity;

FIG. 2 is a top, left, rear exploded perspective view of a two piece 20 pound propane tank cover with access lid according to the invention. The access lid being removed for clarity;

FIG. 3 is a top, right front perspective view of an assembled two piece 20 pound propane tank cover with access lid according to the invention. The access lid being installed and in the closed position;

FIG. 4 is a top, right front perspective view of the invention of FIG. 3 with access lid in the open position. The dash dot lines show the course of the fasteners which keep the access lid in the closed position;

FIG. 5 is a front elevational view of the invention of FIG. 3;

FIG. 6 is a rear elevational view of the invention of FIG. 3;

FIG. 7 is a top plan view of the invention of FIG. 3;

FIG. 8 is a left elevational view of the invention of FIG. 3;

FIG. 9 is a right elevational view of the invention of FIG. 3; and,

FIG. 10 is a bottom plan view of the invention of FIG. 3. The propane tanks are not shown for clarity of detail of the inside of the invention.

The dash double dot lines in FIGS. 1, 2 and 4 are for illustrative purposes only to show the propane tanks the invention covers and form no part of the claimed design.
